Primary Examiner — Andrew Kerr*Assistant Examiner* — Courtney J Clark-Rasheed(74) *Attorney, Agent, or Firm* — Lowe Graham Jones PLLC(57) **CLAIM**

The ornamental design for a mandoline, as shown and described.

DESCRIPTION

FIG. 1 is a top front-left perspective view of a mandoline, showing our new design.

FIG. 2 is a top rear-left perspective view of the mandoline

FIG. 3 is a front elevational view of the mandoline

FIG. 4 is a rear elevational view of the mandoline.

FIG. 5 is a left side elevational view of the mandoline.

FIG. 6 is a right side elevational view of the mandoline aver.

FIG. 7 is a top plan view of the mandoline; and,

FIG. 8 is a bottom plan view of the mandoline.

Features shown in broken lines form no part of the claimed design.
